UNITED STATES PATENT OFFICE.

ETHEL FRANCES GRAHAM, OF WASHINGTON, DISTRICT OF COLUMBIA.

BEACH CAPE.

Application filed August 11, 1925. Serial No. 49,550.

This invention relates to a new and useful improvement in hooded capes and more particularly to that class known as beach capes.

An object of this invention is the provision of a cape made of suitable waterproof material of the lightest and thinnest substance obtainable embodying a toughness of structure sufficient to withstand the usual strain to which such a cape would be subject.

Another object of this invention is the provision of a beach cape which may be worn from the bath house or cottage to the water, and which will be of sufficient length to cover the wearer from head to foot and thus protect her from the torture of sunburn.

A further object of this invention is the provision of a beach cape which may be carried by the wearer, on her person, into the water, thus eliminating the unnecessary delay caused by hiding, checking, or trusting to some one's care, the cape, before entering the water.

A still further object of this invention is the provision of a beach cape which can be worn to the water, then removed, rolled up and concealed within the hood, of said cape, upon the wearer's head and still not spoil the beauty of the headgear.

With the above and other objects in view, this invention resides in the novel features of construction, formation, combinations and arrangement of parts to be hereinafter more fully described, claimed and illustrated by the accompanying drawings, in which:—

Figure 1 is a side elevation of my improved beach cape,

Figure 2 is a front elevation thereof,

Figure 3 is an enlarged sectional view through the headgear and cape, illustrating the cape portion folded within the headgear, and,

Figure 4 is a plain view of the blank formation of my improved cape.

Referring to the accompanying drawings by similar characters of reference throughout numeral 1 indicates the body portion of my improved cape which may be of any desired cut and to the upper edge of which integral therewith is a hood portion 2 rein-

forced by a suitable neck band 3 provided with a suitable fastening means 4 by which said band may be fastened snugly around the neck of the wearer.

55

The body portion 1 is provided at its opposite upper corners with suitable fastening members 5 which permit the fastening together of said corners which will meet at the back of the wearer's neck when said cape or body portion 1 is wrapped about the wearer's body, thus producing a beach cape that will completely envelop the wearer's figure from head to foot, thus protecting said wearer from the penetrating rays of the sun which produce sunburn.

Additional reinforcing bands 6 are provided which are secured at one end to a face reinforcing band 7 then passing over the hood 2, their opposite ends are brought together and joined with the neck band 3. Joined securely to the neck band 3 is a head shield 8 provided as a means for covering the cape portion 1 when same is rolled up and placed within hood 2, thus preventing the cape 1 from coming in direct contact with the wearer's hair, thereby forming a pocket for said cape, as clearly illustrated by Figure 3 of the accompanying drawing, while the reinforcing bands 6 are provided to hold said cape 1 when folded within the hood in a compact position and prevent the undesired movement of same about the wearer's head.

It is now thought that the above description together with the accompanying drawing sufficiently sets forth the construction and method of use in connection with this cape to give those familiar with this art a clear idea as to the construction and wearing of the same.

It should be understood, however, in this connection that various minor changes in the details of construction may be resorted to within the scope of the appended claim, without departing from or sacrificing any of the advantages of this invention.

From the foregoing disclosure, taken in connection with the accompanying drawing, it will be manifest that I have provided a beach cape which will fulfill all of the necessary requirements of such a garment and

which may be adapted for use wherever the services of such a cape may be required.

Having thus fully described this invention, what I claim, and desire to protect by 5 Letters Patent, is:—

A beach cape embodying a body portion, a hood integral therewith, said body portion

being adapted to be folded within said hood, reinforcing members passing around said hood, and means secured to one of said reinforcing members for enveloping said body portion of said cape when folded within the hood.

ETHEL FRANCES GRAHAM.
